UNITED STATES PATENT OFFICE

2,580,440

ABSORPTION REFRIGERATION

Wilhelm Georg Kögel, Stockholm, Sweden, as
signor to Aktiebolaget Elektrolux, Stockholm,
Sweden, a corporation of Sweden

Application March 12, 1946, Serial No. 653,782
In Sweden March 26, 1945

7 Claims. (Cl. 62—119.5)

1

The invention relates to absorption refrigerating apparatus of the continuous inert gas type having a liquid circulating pump which is closed at one end and connected to receive absorption solution at a region removed from the closed end. The invention has for its object to provide an improvement for reducing the vertical height of such refrigerating apparatus, especially when difficulties in maintaining adequate liquid circulation tend to occur in the event the height of the apparatus should be reduced.

It has previously been proposed to use liquid circulating pumps in refrigerating apparatus having a pump chamber arranged as a pocket around the heating flue of the apparatus and to which a vapour lift pipe is connected. The lower end of the pipe extends into the chamber in order to allow a free liquid level to be maintained within the chamber, and a vapour space to be maintained above said level. The pumping is effected due to the increased pressure of such vapour when entering the lower opening of the vapour lift pipe. The vapour bubbles formed in the pump chamber below the liquid level therein and to a region of which absorption solution is supplied will not enter the vapour lift pipe directly, because the upward movement of the vapour bubbles is interrupted in passing above the liquid surface level into the vapour space of the pump chamber. The kinetic energy of the vapour and the liquid moving upwards is therefore lost. According to the present invention the upward movement of vapour bubbles formed in liquid within the pump chamber is advantageously utilized for lifting liquid through the pump section located beyond the pocket.

The invention will be hereinafter more fully described with reference to the accompanying drawing showing diagrammatically embodiments from which characteristic features of the invention will be seen, and of which:

Figs. 1 and 2 show diagrammatically two embodiments of the invention, only those parts of the absorption refrigerating apparatus being illustrated which are of immediate interest in connection with the present invention.

Referring to Fig. 1, in which a flue, a boiler, a liquid circulating pump and a liquid heat-exchanger of a continuously operating absorption refrigerating apparatus are diagrammatically shown, reference numeral 10 denotes a tube employed as a heating flue, such as an iron pipe, for example, numeral 11 denotes the boiler which is heat-conductively connected with the flue, as by welding, and numeral 13 the heat-exchanger

2

of the apparatus which communicates with the boiler 11 through a conduit 12. The upper end of the boiler 11 is connected in a well known manner (not shown) to a rectifier which in turn is connected to the condenser of the apparatus. The boiler pipe 11 is closed at its base and consequently forms a pocket between the point at which conduit 12 is connected thereto and the base, wherein the circulation of liquid mainly takes place due to thermal movement caused by the unsymmetrical heating of the liquid column in the pocket. The poor solution withdrawn through the conduit 12 flows through the exterior jacket of the heat-exchanger 13 to the absorber of the apparatus, not shown.

The liquid circulating pump of the apparatus is denoted by 16 and is in the form of a pipe opening into the top of the boiler pipe 11. The diameter of the pipe is sufficiently narrow so that thermosiphon effect will be created. Rich absorption solution is supplied to the pump through the inner conduit 14 of a heat-exchanger 13. In order to vent gas bubbles which may collect in the conduit 14 it must be connected to the pump at a point located higher than any other part of that conduit. The liquid column in the pump pipe 16 is level with the liquid level in the absorber vessel of the apparatus, not shown, the liquid level in the absorber vessel being indicated in Fig. 1 by the dotted line I. As shown the pump pipe 16 is welded to the flue 10, through which heat is supplied to the pump, through a vertical height which extends a short distance above the liquid level in the absorber vessel. This distance is, however, very short and the reaction head of the pump will therefore be unfavorable. According to the invention this disadvantage is overcome by providing a pipe section 15 of the character shown which extends downwardly reckoned from the point the inner conduit 14 of the heat-exchanger is connected to the lower end of pipe 16, whereby a dead-end pocket is formed through which heat from the flue is supplied to liquid in the pump. In Figs. 1 and 2 the downwardly extending part 15 does not communicate with other liquid quantities located below the connecting point of conduit 14 thereto. It is therefore advantageous to provide an extended part 15 having a larger diameter than that of the pump pipe 16, so that the unsymmetrical heating of the pocket formed by the part 15 will be utilized to induce thermal flow through the entire body of liquid contained in the pocket. The pipe 14 is connected to the part 15 at a region approximately diametrically opposite to

the common generatrix of such part and the flue 10, whereby the cooler entering rich solution flows downwardly along the outer side of the pipe section or part 15. Upward flow of liquid in the part or pipe section 15 is induced due to the lengthwise heating along its line of contact with the flue 10. By providing the downwardly extending part or pipe section 15 the effective reaction head of the pump is altered, because the depth of the pocket formed by the part 15 to a certain degree may be included as a part of the reaction head in addition to the difference in height between the liquid level in the absorber vessel and the point conduit 14 is connected to the part 15. The reaction head constitutes the fluid heads measured from the level at which conduit 14 is connected to the part 15 to the boiler liquid level II and to the absorber level I, respectively.

Fig. 2 shows another embodiment of the device illustrated in Fig. 1, and differs therefrom in that the boiler is not provided with a pocket-shaped extension.

Though as a matter of principle it is unimportant in what way the lower heat-absorbing member or part 15 of the pump is formed, provided free passage in an upward direction exists for the gas bubbles from such part and also from the connecting pipe 14 and circulation or transposition of the liquid contents can be induced, the shaping of the lower part of the pump in accord with the invention will create particular advantages. The possibilities of effecting a regulated thermal flow in the pocket have already been mentioned above. Such flow can be further improved by inserting a partition or a piece of pipe into the member or part 15 to provide two sections into one of which the pipe 14 opens, and which mutually communicate through an interspace in the lowest part of the partition.

The invention is not to be limited to the embodiments shown but may be varied in several ways within the scope of the basic inventive idea. This is applicable especially to the shaping of the base of the pump, the constructions of which may be varied in different respects provided that the abovementioned factors are taken into consideration. The extension of the heat-conductive connection between the pump and the flue may also be varied within wide limits according to the size of the apparatus for which the boiler aggregation is intended. The heat-conductive connection shall, however, extend up to a point located above the liquid level in the absorber vessel.

I claim:

1. In an absorption refrigeration system, a circuit for absorption liquid including an upright riser pipe which is connected to receive liquid at a first level and deliver liquid from a second higher level, said riser pipe having one portion extending downwardly from said first level which is closed at its lower end and forms a dead-end chamber or pocket for fluid, each vertical part of said riser pipe being vertically displaced from adjacent parts so that one portion of said riser pipe does not overlap another portion thereof, said dead-end chamber or pocket and the portion of said riser pipe above said first level having cross-sectional areas large and small enough, respectively, to permit and prevent free relative movement of vapor and liquid therein.

2. Apparatus as set forth in claim 1 including means for heating at least the dead-end chamber or pocket of said riser pipe at only one peripheral

side thereof to effect unsymmetrical heating of the body of fluid therein.

3. Apparatus as set forth in claim 1 including an upright heating flue, at least the larger lower portion of said riser pipe being joined to said heating tube in heat transfer relation therewith on a line substantially parallel to the longitudinal axis of said tube.

4. Apparatus as set forth in claim 3 in which said riser pipe is connected to receive liquid at said first level at a point substantially diametrically opposite the region thereof joined to said heating tube.

5. In an absorption refrigeration system, a circuit for absorption liquid including a vessel and a vertically extending liquid circulator closed at its lower end, a vertically extending liquid heat exchanger having first and second passages, said circulator at a first level above its closed end being connected to receive liquid from the upper end of said first heat exchanger passage and connected to deliver raised liquid from a second higher level to said vessel, the upper end of said second heat exchanger passage being connected to receive liquid from said vessel, the lower portion of said circulator between the closed end thereof and said first level forming a dead-end chamber or pocket for liquid which extends downwardly from the highest point of said liquid heat exchanger, and a vertically extending heating tube, the exterior surface of said heating tube being thermally connected to the exterior surface of the lower portion of said circulator along a vertically extending line to effect heating of liquid in said circulator and form vapor bubbles therein to raise liquid from said first level to said second level by vapor-lift action.

6. In an absorption refrigeration system, a circuit for absorption liquid including a vessel and a vertically extending liquid circulator closed at its lower end, a vertically extending liquid heat exchanger having first and second passages, said circulator at a first level above its closed end being connected to receive liquid from the upper end of said first heat exchanger passage and connected to deliver raised liquid from a second higher level to said vessel, the upper end of said second heat exchanger passage being connected to receive liquid from said vessel, the lower portion of said circulator between the closed end thereof and said first level forming a dead-end chamber or pocket for liquid which extends downwardly from the highest point of said liquid heat exchanger, and a vertically extending heating tube, said liquid heat exchanger being in the form of a coil which is disposed about said heating tube and the lower portion of said circulator, and means for thermally connecting the exterior surface of said heating tube to the exterior surface of the lower portion of said circulator along a vertically extending line to effect heating of liquid in said circulator and form vapor bubbles therein to raise liquid from said first level to said second level by vapor-lift action.

7. In an absorption refrigeration system, a circuit for absorption liquid including a vertically disposed vessel and a vertically extending liquid circulator closed at its lower end, a vertically extending liquid heat exchanger having first and second passages, said circulator at a first level above its closed end being connected to receive liquid from the upper end of said first heat exchanger passage and connected to deliver raised liquid from a second higher level to said vessel, the upper end of said second heat exchanger

passage being connected to receive liquid from said vessel, the lower portion of said circulator between the closed end thereof and said first level forming a dead-end chamber or pocket for liquid which extends downwardly from the highest point of said liquid heat exchanger, and means including a vertically extending heating tube for heating said vessel, the exterior surface of said heating tube also being thermally connected to the exterior surface of the lower portion of said circulator along a vertically extending line to effect heating of liquid in said circulator and form vapor bubbles therein to raise liquid from said first level to said second level by vapor-lift action, and said liquid heat exchanger being in the form of a coil which is disposed about the lower por-

tion of said circulator and also about said heating tube at a region between the upper and lower ends of the latter.
